UNITED STATES PATENT OFFICE

FREDERICK HANLAN, OF BATTLE CREEK, MICHIGAN, ASSIGNOR TO H. B. SHERMAN MANUFACTURING COMPANY, OF BATTLE CREEK, MICHIGAN, A CORPORATION OF MICHIGAN

SPRAY HEAD

Application filed July 30, 1932. Serial No. 627,394.

This invention is an improvement in lawn sprinklers or spray heads of the type which are ordinarily connected in series by short lengths of hose. When such heads as heretofore constructed are so connected and the hose coupled fast at either end and the water pressure is turned on there is a tendency for the hose to twist and tip the sprinkler heads up, or over. The hose is apt to be somewhat twisted when empty of water and water pressure tends to straighten it out and produce a convulsively twisting motion in the hose and if the spray head is connected rigidly between the lengths of hose it is not heavy enough to overcome this twisting motion.

One object of the present invention is to prevent twisting of the hose connected to the spray head overturning or affecting the operative position of the spray head. Another object of the invention is to simplify and improve the construction of the spray head.

In the accompanying drawing I have illustrated a spray head embodying the invention, and will describe the same with reference thereto, and summarize in the claims the novel features of the invention for which protection is desired.

In said drawing:

Fig. 1 is a perspective view of one of the spray heads connected to hose sections.

Fig. 2 is a longitudinal vertical section through the spray head.

Fig. 3 is a section on the line 3—3, Fig. 2.

The spray head shown comprises a tubular body portion 1 made out of drawn sheet metal and having one end exteriorly threaded as at 1a for the engagement of the female member 8 of an ordinary hose coupling attached to a hose section H. The other end of this body is unthreaded and inturned. The body 1 is preferably made of drawn brass and is provided on its upper side with an integral hollow annular boss 1b which is pressed out of the metal of the body and is provided with a central aperture 1c for the escape of water. Within this boss is secured a perforated disk 3 which is provided with spaced openings 3a for the passage of water and which cause the water to be disseminated before it reaches the

opening 1c and to issue as a spray through the opening 1c.

In the lower side of the body is an approximately oval shaped hollow protuberance 1e pressed out of the metal of the body and adapted to fit in and project through an opening in the transversely disposed base member 6, and its outer end is swaged to lock the body 1 securely to the base; see Figs. 1 and 3.

Connected with the unthreaded end of the body 1 is a female coupling member 4 whose outer end is internally threaded for engagement with the male member 8a of an ordinary hose connection attached to a hose section H', Figs. 1 and 2. The shank of the coupling member 4 is rotatably entered within the unthreaded end of the body and is provided with an annular groove for the reception of a washer 5. Preferably this shank is provided with an annular bead or bend 4b at its inner end and with another annular bead or bend 4c spaced from the bend 4b, the exterior space between the beads 4b, 4c forming an annular groove for the reception of the washer 5. The beads 4b, 4c are slightly less in exterior diameter than the internal diameter of the body 1.

The coupling member 4 being rotatably connected to the body forms a swivel connection between the body and hose section H' as indicated in Figs. 1 and 2; if there is any twisting or buckling of the hose when the water pressure is turned on such swivel connection between the hose and the sprinkler head permits the hose to twist but the spray head to remain in proper working position.

In assembling the parts the washer 5 is placed in the channel between beads 4b, 4c then the shank of coupling member 4 is inserted in the unthreaded end of the body 1, the washer 5 fitting closely between the exterior of the shank and the interior of the body as shown in Figs. 2 and 3, then the outer extremity of the unthreaded end of the body is turned in against the outer side of the rib 4c as indicated at 1f and permanently connects the coupling member 4 to the body but permits it to turn therein.

The washer 5 is preferably a split washer, as shown in Figs. 2 and 3 so that the water

- pressure will spread the washer and force it against the opposed walls of the body and shank and create a tight joint. Other suitable packing such as a soft spongy packing 5 or a cup washer, which under water pressure will make a tight joint, might be used. The construction is such that at the female end of the sprinkler head there is a swivel motion between the hose and head regardless of 10 how tightly the coupling 8a is screwed in, with the result that the sprinkler head becomes self aligning and when the hose twists it does not raise or turn over the sprinkler head.
- 15 This same spray head may be used as a single sprinkler by detaching hose H therefrom and applying an end cap 7 as indicated in Fig. 3 and the twisting of hose H' would not affect or displace or overturn the sprinkler.

I claim:—

1. A sprinkler head comprising a body having one end threaded for engagement with a member of an ordinary hose connection, a 25 coupling member having a threaded outer end for engagement with a member of an ordinary hose connection and a shank portion entered into the unthreaded end of the body and rotatably confined thereto by the 30 inturned end of the body engaging the outer side of the adjacent bead, and a washer on the shank forming a tight joint between the shank and the body.
2. A sprinkler head comprising a body having one end threaded for engagement with a member of an ordinary hose connection, a coupling member having a threaded outer end for engagement with a member of an ordinary hose connection and a shank portion 40 having spaced annular beads entered into the unthreaded end of the body and rotatably confined thereto by the inturned end of the body engaging the outer side of the adjacent bead, and a washer interposed between the beads and forming a tight joint between the shank and the body.
3. A sprinkler head comprising a cylindric body of drawn sheet metal having one end threaded for engagement with a member of an ordinary hose coupling member and having a lateral outwardly projecting boss provided with an aperture for the escape of water, a drawn metal coupling member having its outer end threaded for engagement with a member of an ordinary hose coupling and having a shank portion entered into the unthreaded end of the body and confined therein by the inturned end of the body, and a washer forming a tight joint between the shank and the body.
4. A sprinkler head comprising a cylindric body of drawn sheet metal having one end threaded for engagement with a member of an ordinary hose coupling member and having a lateral outwardly projecting boss 65

provided with an aperture for the escape of water, a drawn metal coupling member having its outer end threaded for engagement with a member of an ordinary hose coupling and having a shank portion formed with 70 spaced annular beads entered into the unthreaded end of the body and confined therein by the inturned end of the body engaging the outer side of the adjacent bead, and a washer interposed between the beads forming a tight joint between the shank and the body.

5. A sprinkler head comprising a cylindric body portion made of drawn sheet metal having one end threaded for engagement with a member of an ordinary hose coupling and having a lateral outwardly projecting integral boss provided with an aperture for the escape of water, and an integral outwardly pressed lug opposite the boss for engagement with a base member; a drawn metal coupling member having a threaded outer end for engagement with a member of an ordinary hose coupling and having a shank portion provided with spaced annular beads and entered into the unthreaded end of the body and confined therein by the inturned end of the body engaging the outer side of the adjacent bead, a washer between the beads forming a tight joint between the shank and the body, and a transverse base member having an opening into which the lug on the body is entered, said lug being swaged in said opening to fasten the body to the base.

6. A sprinkler head comprising a body having an outlet orifice, means to prevent rotation of the body; a coupling member having a threaded outer end for engagement with a member of an ordinary hose connection and a shank portion having beads entered into the unthreaded end of the body and rotatably confined thereto by the inturned end of the body engaging the outer side of the adjacent bead, said shank having an annular washer receiving recess, and a washer in said recess forming a tight joint between the shank and the body.

7. A sprinkler head comprising a cylindric body of drawn sheet metal having a lateral outwardly projecting boss provided with an aperture for the escape of water, a base supporting the body, a drawn metal coupling member having its outer end threaded for engagement with a member of an ordinary hose coupling and having a shank portion formed with spaced annular beads entered into one end of the body and confined therein by the inturned end of the body engaging the outer side of the adjacent bead, and a washer interposed between the beads forming a tight joint between the shank and the body.

FREDERICK HANLAN.
